UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

ETHEREAL-WAVE-RESPONSIVE DEVICE.

1,096,142.

Specification of Letters Patent. Patented May 12, 1914.

Application filed October 27, 1909, Serial No. 524,946. Renewed November 9, 1912. Serial No. 730,497.

To all whom it may concern:

Be it known that I, EZECHIEL WEINTRAUB, a citizen of the United States, residing at Lynn, county of Essex, State of Massachusetts, have invented certain new and useful Improvements in Ethereal - Wave - Responsive Devices, of which the following is a specification.

My present invention comprises an improved means for detecting and indicating ethereal vibrations, such as those used in the art of wireless signaling, or in bolometric measurements and determination.

Of the wave-detecting devices used for wireless telegraphy and telephony, some are based on the changes of resistance indicated by a conductor when heated by the high frequency waves received from the antenna of the station. Others owe their wave-detecting power to a change in the electrical action of a loose contact between two dissimilar conductive elements. In some cases advantage is taken of the rectifying action and the generation of a thermal electromotive force at the junction between suitable materials. In the Langley bolometer the waves emanating from a light-giving source change the temperature of the receiving element, thereby changing its resistance, and, through the instrumentality of a suitable indicating instrument, giving information concerning the temperature of the source of light.

My present invention embraces an improvement in the various types of wave-detecting instruments above mentioned, by the use of boron or a boron alloy for at least one of the wave-responding elements of the device.

In the accompanying drawing, Figure 1 indicates diagrammatically a system of connections in which a boron conductor gives indications in a telephone because of its change in resistance when heated by energy received over the antennæ; Fig. 2 is a similar diagram, showing a receiver based primarily on the use of a limited contact between the two active elements; Fig. 3 shows how the electromotive force at the junction between two elements can be used to indicate conditions on the antenna.

Many of the standard text books refer to the production of magnesium borid by reduction of boric anhydrid with magnesium, but prior to my own work in this field,

Moissan is the only experimenter of recognized reputation who even claims to have produced pure boron. Moissan sought to prevent the retention of magnesium in the final product by using an excess of the boric anhydrid. He described the product as analyzing 93 to 95 per cent. boron, and as being a brownish powder, practically non-conductive for electricity and vaporizable without fusion. I am convinced that this material was not relatively pure boron, as Moissan supposed, but was in fact a boron suboxid associated with more or less magnesium borid.

I have discovered that elemental boron possesses properties which are altogether different from those possessed by the so-called boron referred to above. Pure or elemental boron can be fused into a dense body, which is black in color and has a conchoidal fracture. It is a fair conductor of electricity, and has a negative temperature resistance co-efficient of a magnitude without precedent among the chemical elements. I have found that at ordinary room temperatures the conductivity of pure boron doubles approximately. In changing from room temperature to 400 degrees C., it changes according to the ratio of about one to two million. I have also found that the action of boron as a thermo-electric generating element is relatively strong. Claims on the boron thermo-couple have been made in Patent No. 1,079,621 of November 25, 1913.

The valuable properties of high resistance and the enormous resistance change can be varied within certain limits, so as to adapt them best to practical requirements, by associating with boron small amounts of other elements, such as silicon, magnesium, aluminium and especially carbon. The initial resistance is then lowered, and the negative temperature resistance coefficient is also somewhat reduced, depending upon the amount of carbon added.

For a full disclosure of my invention, I will first describe some methods for making pure fused boron. According to one process, boron chlorid is reduced with hydrogen in a high voltage alternating current arc maintained between water-cooled copper electrodes, as fully disclosed by me in my Patent No. 1,046,043. During the process of manufacture some of the reduced boron fuses on the ends of the electrodes and grows into

beads or rods. Boron in this form can be applied directly to wave-detecting instruments. Some of the reduced boron, however, is thrown out by the arc as a powder on the walls of the arc chamber. This powder 5 is compressed into a stick, and is then fused in a high potential arc operating in hydrogen, using the stick of boron as an electrode. The process and apparatus for 10 carrying out this fusion by means of the high potential arc are fully described by me in my Patent No. 1,019,392. The fused product is used in a wave-detecting instrument.

According to another mode of manufacture, 15 an excess of boric anhydrid is first reduced with magnesium. The resulting product consists of magnesium borid, or boron suboxid, or a mixture of both, according to the temperature at which the reaction is carried on. It can be made to yield fused, 20 substantially pure boron by preheating it in a vacuum furnace to drive out some of the impurities and make it partially conductive, and then heating this stick by making it the 25 electrode for a high potential alternating current arc operating in hydrogen at a pressure of about five inches of mercury, or by making it the electrode of a mercury-vapor arc. Claims are made on some of the above 30 features in my Patent No. 997,879.

If it is desired to associate with the boron a certain amount of carbon or other element, this can be accomplished by one of the following methods: A carbon filament 35 is heated in a mixture of boron chlorid and hydrogen, which results in the deposition of boron on the filament. During this process, especially if the temperature is raised considerably, the carbon diffuses through 40 the mass of boron. If a perfectly homogeneous product is desired, the mass is fused in a high potential, or mercury arc. As it is possible to use a carbon fillet possessing very small mass, the percentage of carbon can be 45 made practically as small as desired by this method. If higher percentages of carbon are desired, a gaseous carbon compound, such as vaporized gasolene or carbon tetrachlorid, is added to the mixture of boron 50 chlorid and hydrogen, which results in the deposition of carbon simultaneously with the deposition of boron. These steps are disclosed in my Patent No. 1,019,393. By varying the amount of vapor of the carbon 55 compound in the mixture, the carbon content may be varied at will. When the addition of carbon amounts to as much as 20 per cent., the temperature coefficient of the product is of the same general magnitude as that 60 of pure carbon, or, in other words, very much less than that of pure boron.

In Fig. 1, I have shown a grounded antenna 1 equipped with the usual local circuit, including a condenser 2, an inductance 3, a local battery 4, and a telephone 65

or other indicating instrument 5 all connected in series, as indicated in the drawing. In shunt with a part of this local circuit is a boron element 6, of suitably small cross section, and serving as a wave-responsive device for the local circuit. Energy received over the antenna 1 will be transferred to the boron conductor 6, and there converted into heat, which will so change the conductivity of the boron as to vary the current 70 applied to receiver 5 by the local battery 4. For this purpose a boron element possesses the very important requisites of high initial resistance combined with an enormous temperature resistance coefficient. The battery 75 4 should be of such low voltage that the boron element will radiate heat with sufficient rapidity so as not to run away, but will resume its high resistance as soon as the high potential oscillations have passed. In 80 some cases the battery 4 can be entirely dispensed with, the energy for operating the indicating instrument 5 being part of the energy received by the antenna.

Although I have shown the use of an antenna and other conductive elements for applying the vibratory energy to the boron element, it will be apparent that the energy might be initially in the form of light or heat when applied directly to the boron 90 element, according to the general methods made public by Professor Langley and others in their many publications concerning the instrument known as a "bolometer."

In Fig. 2, the boron element 7 makes but 100 limited contact with the copper block 8. In this case, energy received over the antenna 9 will be transferred through the inductive connection 10, and the usual condenser 11, and will pass through the point of contact between the boron block 7 and the copper block 8, thereby locally heating the boron, and not only bringing into play the enormous negative temperature coefficient 105 of the boron, but also establishing a thermoelectromotive force operative to increase the effect of the local battery 12 on the telephone 110 or other indicator 13. It may be noted that for this purpose, copper and boron are specially adapted for use in contact, as the low 115 chemical affinity of one for the other greatly lessens the danger of fusion at the point of contact.

In Fig. 3 the local battery is dispensed with, and the wave-detecting action of the 120 boron element 4 is based on the generation of a thermo-electromotive force between the boron and the conductive element 15 of other suitable material with which it is in good contact. This electromotive force 125 serves to establish the flow of current through the path, including an inductance 16, and a galvanometer, or other suitable indicating instrument 17.

The embodiments above described will 130

serve to indicate the generic character of my present invention, but I desire that they shall be considered as merely illustrative and by no means exhausting the possibilities 5 arising from my discoveries in connection with pure fused boron.

I am aware that boron can with advantage be substituted for other material as the active element in many different types of 10 wave-detecting instruments, and I desire that the present specification shall indicate my appreciation of that possibility.

What I claim as new and desire to secure by Letters Patent of the United States, 15 is:—

1. A wave-responsive element, comprising essentially conductive boron.
2. A wave-responsive element composed mainly of boron and small amounts of other 20 elements.
3. A wave-responsive element, comprising essentially fused conductive boron, associated with a small amount of a more conductive material.

4. A wave-responsive device composed 25 essentially of boron and small amounts of carbon.

5. A receiver for radiant energy comprising two conductive elements, one at least of which is composed essentially of boron. 30

6. A receiver for radiant energy comprising two conductive elements, one of which consists essentially of boron and the other of which is copper.

7. In a wave-responsive device, a copper 35 block making limited contact with a block consisting largely of uncombined conductive boron.

8. In a system of signaling by electromagnetic waves, a receiver comprising a 40 thermo-couple having an element consisting largely of boron.

In witness whereof, I have hereunto set my hand this 26th day of October, 1909.

EZECHIEL WEINTRAUB.

Correction in Letters Patent No. 1,096,142.

It is hereby certified that in Letters Patent No. 1,096,142, granted May 12, 1914, upon the application of Ezechiel Weintraub, of Lynn, Massachusetts, for an improvement in "Ethereal-Wave-Responsive Devices," an error appears in the printed specification requiring correction as follows: Page 1, transpose lines 81 and 82; and that the said Letters Patent should be read with this correction therein that the same may conform to the record of the case in the Patent Office.

Signed and sealed this 16th day of June, A. D., 1914.

[SEAL.]

J. T. NEWTON,

Acting Commissioner of Patents.
